UNITED STATES PATENT OFFICE.

REINHOLD BOEKLEN, OF BROOKLYN, NEW YORK, AND WALTER S. WRIGHT,
OF CHICAGO, ILLINOIS.

GAS-GENERATING APPARATUS.

SPECIFICATION forming part of Letters Patent No. 416,047, dated November 26, 1889.

Application filed March 5, 1889. Serial No. 301,880. (No model.)

To all whom it may concern:

Be it known that we, REINHOLD BOEKLEN, residing at Brooklyn, in the county of Kings and State of New York, and WALTER S. WRIGHT, residing at Chicago, in the county of Cook and State of Illinois, both citizens of the United States, have invented certain new and useful Improvements in Gas-Generating Apparatus; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention is designed particularly to apply to apparatus for generating what is known as "water-gas."

The object of the invention is to provide an apparatus whereby ordinary coal and water gas may be made from the same coal, and particularly from ordinary bituminous coal. Briefly stated, the result accomplished is the distillation of bituminous coal within the apparatus and the withdrawal of the resultant gases and the subsequent heating of the resultant coke to incandescence and passing steam through such coke to decompose the steam and form water-gas, the entire operation being performed within the same apparatus, the heat for the distillation of the coal being supplied by the burning coke. This method is adopted because of its economy. In the ordinary distillation of coal a certain amount of fire is needed for heating the retorts containing the coal. By the ordinary method of distilling coal such a fire is an extra expense. In the manufacture of water-gas by the ordinary processes, considerable heat is wasted during the process of igniting the bed of coal and coke in which the steam is decomposed. By our process the water-gas fire is made to heat the retorts, and the coke resulting from the distillation of the coal is added to the bed of water-gas fuel without loss of heat, so that the temperature of said fuel is always high. The two kinds of gas may be led off separately for separate purifying and storage, or they may be combined and used as one gas.

Either or both may also be carbureted to acquire illuminating power.

The improvement which constitutes the subject-matter of this application is an addition to or modification of the improvements made the subject-matter of a sole application by Reinhold Boeklen, Serial No. 301,879, who now joins in this application, and filed of even date herewith, and two sole applications, Serial Nos. 301,869 and 301,870, by Walter S. Wright, who now joins in this application, also filed of even date herewith, each of said sole applications being for Letters Patent of the United States for improvements in gas-generating apparatus.

In the accompanying drawings, Figure 1 is a vertical central section of a cupola A embodying our improvement. Fig. 2 is a vertical central section of the upper portion of said cupola, taken at right angles to the section shown in Fig. 1. Fig. 3 is a horizontal section in line $x-x$ of Fig. 2. Fig. 4 is a plan of the apparatus. Fig. 5 is a detail view.

Referring to Figs. 1 and 2, the apparatus consists of a general inclosure or cupola A, the lower portion of which B is used as a combustion-chamber, while the upper portion C is used for the distillation of the coal and for superheating the water-gas. The inclosure A is built up in the usual way of fire-resistant material—such as clay, tile, or brick—and is covered over its outer faces with metallic plate. It is also provided with heat-resisting and gas-tight doors and ports in the places hereinafter mentioned.

The portion B of the cupola may be constructed in any of the well-known forms and operated according to any of the ordinary methods of generating water-gas. The parts relating thereto, as shown in the drawings, are merely for illustration.

B' is a common grate, upon which the bed of fuel is supported. Any other form of grate may be used in lieu of this. At a suitable distance above the grate is a sealed door B², which affords access to that portion of the cupola which is to receive the fuel for the incandescent bed.

B³ B³ designate ash-doors below the grate.

B⁴ is an air-blast pipe leading through the

wall of the cupola, below the grate. This may also enter above the grate, as shown by Fig. 1, and it is provided with one or more valves b^4 .

5 B⁵ designates steam-nozzles entering the cupola just above the grate, by which steam is introduced to pass through the bed of incandescent fuel resting upon the grate. An annular chest incloses the steam-pipe b^5 , 10 from which the nozzles B⁵ receive their steam. Said steam pipe and chest may extend partially or wholly around the cupola. The chest serves as a heated chamber within which the steam-pipe b^5 is heated.

15 The portion C of the cupola A is preferably expanded laterally and provided at its sides with vertical retorts C', extending from the outer wall toward the center of the cupola and nearly meeting at such center. The 20 drawings show four such retorts; but the number may of course be varied. The drawings also show the cupola as being round in cross-section. Other shapes may be used, if desired. The dome-shaped arch C² rises from 25 the upper limit of the portion B of the cupola and is continued in a hollow chamber C³, the upper end of which is covered by a door C⁴, and from the side of which leads a pipe G. Around the sides of the arch C² are 30 openings D. The retorts C' are L-shaped, the long arm rising vertically to and through the upper wall of the cupola, and the short arm extending horizontally through the side wall of the cupola, where an ordinary seal-door E is applied. At the upper end a seal-door F is applied, and a pipe J is led off horizontally. The lower side of the angle formed 35 at the elbow in the retorts rests upon the arch C², while just above said elbow a passage E' extends through the retort into the neck between the arch C² and the chamber C³. The 40 ends of the passages E' nearest the center of the cupola are made to slope at the top toward such center, so that they together form 45 a space like a hollow truncated pyramid or cone. Said ends of said passages are suitably faced to form smooth seats.

E² is a head of the same general shape as the space between said ends, so that when 50 said head is drawn upwardly between said ends the latter are closed and sealed. Said head may be of plain form and composed of ordinary heat-resisting material. The drawings show a valve-stem e², seated loosely in an 55 upward continuation of said head, and said stem extends upwardly through the cover C⁴, where it is arranged to be raised by means of a crank-wheel E³. The drawings show a special device for sealing the ends of the passage 60 E'. The main portion of said head is made of heat-resisting material, while the sides have recesses e' of proper size to receive plates e³, suitably hinged to said head at their upper ends and joined at their middle by links e⁴ 65 to the lower end of said stem.

The action of this special apparatus is as follows: When said stem is drawn upwardly,

said head is also raised and said links are drawn into line, so as to force said plates e³ outwardly away from said head against the 70 ends of said passages, thus at the same time completely sealing the retorts and chamber C³ away from each other and the remainder of the cupola. The pipe G and the pipes J lead to the wash-box H. At one side of the 75 cupola, as shown in the drawings, or on top of the cupola, as shown by the dotted circle, there is located an exit-pipe I, with a door I' upon its top. At the side of said pipe I a pipe I² is connected and leads thence to the 80 wash-box. Suitable floors L L may be provided to afford access to the different portions of the apparatus. It is to be observed that by this arrangement of the retorts they are entirely surrounded by free space, and 85 that the group of retorts is sealed at the middle of the cupola by a single valve apparatus.

The operation is as follows: The bed of coal or coke is first placed upon the grate B' to a sufficient depth for decomposing steam 90 to form water-gas, said bed being provided with kindling or otherwise for readily igniting the same. The kindling may first be arranged upon the grate through the door B². Then the coal is fed in through the same door, 95 after which the latter is sealed. The valve at E' being closed the retorts C' are filled with coal through the doors F, the doors E being first sealed. The door I' is now opened and the charge upon the grate B' is ignited 100 and the fire urged by a blast from the blast-pipe B⁴. The gaseous products of this combustion rise upwardly and pass the openings D in the arch C² and all around the retorts C', and thence out through the exit-pipe I 105 and door I' into the outer air; or they may be led thence and utilized as "producer gas." By this means each of the retorts C' is well heated simultaneously with the ignition of the bed of material upon the grate. Thus the 110 distillation of the coal in the retorts is established and continued so long as the apparatus remains hot. The gases resulting from such distillation in the retorts rise and escape through the pipes J into the wash-box H. 115 When the bed of material upon the grate B' has been sufficiently ignited for the decomposition of steam, the blast-pipe B⁴ and the door I' are closed and the steam-nozzles B⁵ are opened. Thus steam is delivered through 120 the bed of incandescent material and decomposed in the well-known manner, the gases resulting being hydrogen and carbonic oxide or hydrogen and carbonic acid. If, when the bed of incandescent material has cooled, the 125 coal in the retorts has not been fully distilled, then the steam is shut off, the door I' and the blast-pipe B⁴ again opened, and the mass of material upon the grate again raised to the required temperature, and said blast-pipe B⁴ 130 and door I' again closed, and the steam again turned on, and so on until the coal in the retorts has been fully distilled and only coke remains in the retorts. Now the grate B' may

be cleared of ashes and cinders and the mass of fuel thereon allowed to settle, then the head E² lowered, as shown in Fig. 2, so as to open the passages E'. Then by opening the 5 doors E the coke in said retorts may be pushed inwardly through the passage E' and allowed to fall downwardly upon the burning bed of fuel below, so that the depth of fuel necessary for the decomposition of steam is restored. 10 Then the head E² is again raised, the doors E sealed, and the retorts refilled with coal through the doors F. The blast of air is again turned on to "blow up" the mass of material upon the grate and the new charges of coal 15 in the retorts are heated and distilled. While the head E² is down, the gases within the cupola may rise through the chamber C³ and pass away through the pipe G to the wash-box. It will be seen that when the distillation is progressing and the water-gas is being formed by the decomposition of the steam, the two kinds of gas are being formed simultaneously and passed separately into the wash-box. This is done when it is desired to mix 20 the two kinds of gas and consume them as a mixture. It will be seen, however, that the pipes conveying the two kinds of gas may lead to two distinct wash-boxes and the latter communicate with distinct mains or holders, 25 so that each kind of gas may be consumed separately, for the purpose desired. Either or both of the gases may be carbureted by mixing the same with vaporized petroleum or other liquid hydrocarbon. 30 It is to be observed that the entire inclosure or cupola A is a unitary-heated chamber and that the decomposing bed of fuel and the distilling-retorts are located within such chamber, and that the coke produced by distilling the coal in the retorts does not leave 35 said chamber, but remains and is consumed therein, it being transferred only from one portion of said chamber to another. Thus the heat of the coke is preserved to aid in 40 burning it when it reaches the fuel-bed.

We claim as our invention—

1. In a gas-generating cupola, a grate and steam-inlet located in the lower portion of said cupola, a space for a bed of carbonaceous material above said grate, an arch C², having passages D and resting upon the walls of the cupola near the middle of the latter, a chamber C³, rising through said arch,

L-shaped retorts located in the space between said chamber C³ and the outer wall of the cupola and resting upon said arch, said retorts having suitable coal-inlets and gas-outlets above and said retorts and chamber C³ communicating into a common space in the upper portion of said arch, and a suitable sealing-head arranged to be fitted over the openings from said retorts and said chamber C³, substantially as shown and described. 55 2. The combination, with a gas-generating cupola having in its lower portion a grate and steam-inlets and a space for a bed of carbonaceous material above said grate, and an arch C² in passages D near the middle of said cupola, of a chamber C³, opening at its lower end into the upper portion of said arch, 60 and L-shaped retorts having their vertical arms extending through the upper wall of the cupola and their horizontal arms extending through the lateral walls of the cupola and communicating at their elbows with the 65 upper portion of the said arch, and a sealing-head arranged to be fitted over the openings from said retorts and over the opening from the chamber C³, substantially as shown and described. 70 3. In a gas-generating apparatus, the combination of the coal-distilling retorts having coke-outlets directed toward each other, and a sealing-head having the plates e³, links e⁴, and valve-stem e², arranged and operating 75 substantially as shown and described. 80 4. In a gas-generating apparatus, the combination, with a cupola A, of coal-distilling retorts arranged within said cupola and having coke-outlets directed toward each other, 90 a sealing-head E², arranged to rest over said outlets, a valve-stem e², rising from said head through the upper portion of the cupola, and a suitable crank-wheel connected with said valve-stem for actuating the latter and said 95 sealing-head, substantially as shown and described.

In testimony whereof we affix our signatures, in presence of two witnesses, this 12th day of February, 1889.

REINHOLD BOEKLEN.
